UNITED STATES PATENT OFFICE.

PELHAM E. CAUTHORN, OF DENVER, COLORADO.

TRACK-GAGE ATTACHMENT FOR HAND-CARS.

1,110,894.

Specification of Letters Patent. Patented Sept. 15, 1914.

Application filed April 28, 1914. Serial No. 834,991.

To all whom it may concern:

Be it known that I, PELHAM E. CAUTHORN, a citizen of the United States, residing at Denver, in the county of Denver and State 5 of Colorado, have invented new and useful Improvements in Track-Gage Attachments for Hand-Cars, of which the following is a specification.

The invention relates to gage devices, and 10 more particularly to the class of track gage attachments for hand cars.

The primary object of the invention is the provision of an attachment of this character wherein the same when not in use can 15 be readily folded against the supports therefor at the front end of the car, and is readily accessible for the bringing of the same into operative position.

Another object of the invention is the 20 provision wherein the same will automatically operate for indicating the gage of a track when the car is traveling thereon, the gage attachment being of novel form and is readily and easily brought into operative position so as to move 25 over the track for indicating any irregularity in the same.

A further object of the invention is the 30 provision of an attachment of this character which is extremely simple in construction, reliable and efficient in operation, and inexpensive in manufacture.

With these and other objects in view, the invention consists in the construction, combination and arrangement of parts as will 35 be hereinafter fully described, illustrated in the accompanying drawing, and pointed out in the claim hereunto appended.

In the drawing:—Figure 1 is a top plan view of a hand car of the ordinary well-known construction, with the gage attachment 40 constructed in accordance with the invention applied thereto. Fig. 2 is a vertical sectional view on the line 2—2 of Fig. 1. Fig. 3 is a sectional view on the line 3—3 45 of Fig. 1.

Similar reference characters indicate corresponding parts throughout the several views in the drawing.

Referring to the drawing in detail, A 50 designates a hand car of the usual construction, which is operated by means of the walking beam B, having the handles C, and D the rails of the track laid in the ordinary well-known manner.

The gage attachment comprises a pair of 55 brackets 10, which are bolted or otherwise

secured to the floor or platform of the car A at its front end, the forwardly inclined portions 11 of which extend beyond the car and are formed with pivot sleeves 12 in which is 60 journaled a pivot shaft 13 of the gage frame hereinafter fully described. The gage frame comprises spaced parallel side bars 14 which are disposed transversely with respect to the car and track and are connected 65 together at intervals with cross pieces 15, each formed with intermediate and outer sleeves 16 and 17 respectively, the latter sleeves receiving the bars 14 which are fixed 70 therein in any suitable manner, while slideable in the sleeves 16 are gage rods 18, the outer ends of which form spindles for the gage wheels 19 adapted to travel on the rails of the track, the wheels being flanged as usual to contact with the inner surfaces 75 of the balls of the rails.

Slidably connected to the side bars 14 of the frame and fixed to the rods 18 are cross heads 20, while surrounding these rods 18 and bearing against the cross heads 20 and the cross pieces 15 adjacent thereto at the inner sides of the same are coiled expansion springs 21 which automatically move the rods outwardly to hold the flanges on the 80 wheels 19 engaged with the track, the pivot 85 shaft 13 being connected to a pair of the cross pieces 15 by means of extensions 22 thereof.

The inner ends 23 of the rods 18 are offset due to curvatures therein to overlie a 90 gage plate 24 suitably fixed in the frame centrally thereof, the plate being provided on its outer face with suitable scale indicia 95 25 over which move the gage pointers 26 on the ends 23 of the rods 18 so that the respective scale indicia and pointers 26 cooperate to enable a track hand to determine 95 with accuracy the gage of the track when the hand car is traveling thereover.

The gage attachment when not in use is 100 swung upwardly and rearwardly so that its frame will rest against the inclined portions 11 of the brackets mounted at the front of the car, and will be conveniently held in such position for accessibility whereby it 105 may be brought into use when the occasion requires.

On the pivot shaft 13 at opposite ends thereof are mounted collars 27 carrying binding screws 28 which adjustably fasten 110 the said collars on the shaft. Arranged between the sleeves 12 of the brackets and the

collars 27 are coiled tension springs 29 which surround the shaft 13, and in this manner the gage frame is supported for lateral displacement against the resistance of the 5 springs 29 on the pivot shaft connecting the frame to the bracket.

From the foregoing it is thought that the construction and manner of use of the device will be clearly understood, and therefore a more extended explanation has been omitted.

What is claimed is:—

A gage attachment for hand cars comprising a frame, means adapted to be mounted on the car and swingingly supporting the said frame, a gage plate carried

by the frame and having indicia thereon, gage rods slidably supported in the frame and having pointers traversable over the gage plate, gage wheels journaled at the 20 outer ends of the said rods, means for extending the said rods away from each other, guide pieces in the frame and supporting the said rods, the said means on the car having rest portions for the said frame 25 when swung to inoperative position.

In testimony whereof I affix my signature in presence of two witnesses.

PELHAM E. CAUTHORN.
